UNITED STATES PATENT OFFICE.

ALFRED M. DEMUTH, OF SAN FRANCISCO, CALIFORNIA,

MEAT-PRESS.

1,249,348.

Specification of Letters Patent. Patented Dec. 11, 1917.

Application filed August 22, 1916. Serial No. 116,244.

To all whom it may concern:

Be it known that I, ALFRED M. DEMUTH, a citizen of the United States, residing at San Francisco, in the county of San Francisco and State of California, have invented new and useful Improvements in Meat-Presses, of which the following is a specification.

This invention relates to an improved device for compressing joints of meat, and especially boned hams.

The object of the invention is to provide a press which can be easily and quickly operated, which can be adjusted for joints of different sizes, and which will leave the joint with approximately square ends.

In the accompanying drawing, Figure 1 is a broken side view of my improved meat compressor; Fig. 2 is a cross sectional view on the line 2—2 of Fig. 1; Fig. 3 is an end view thereof; Fig. 4 is a broken side view of a modification of the invention; Fig. 5 is a broken side view of a further modification; Fig. 6 is a transverse section on the line 6—6 of Fig. 5.

Referring to the drawing, 1, 2 indicate standards, to the upper portions of the opposing faces of which are connected, by screws 3, the ends of a bar 4. From said upper portions and bar extend on each side circularly curved arms 6, 7, which are riveted, as shown at 8, to a stationary semi-cylindrical press section 9, to one longitudinal upper edge of which is hinged, as shown at 11, a movable semi-cylindrical press section 12. Near the other longitudinal edge of said movable section are hinged catches 13, here shown as three in number, having slots 14, through which can pass the free ends of curved bars 16, hinged, as shown at 17, to the bar 4, and all connected with each other, so as to swing together, by a longitudinal rod 18. Each bar is formed on its outer edge near its free end with a series of hooks or teeth 19, adapted to engage the outer end of the slot 14 through which the bar passes. To the outer side of the movable press section, somewhat nearer its free than its hinged edge, are secured radially 50 extending handles 21.

22, 23 indicate heads for the press, the head 22 being formed integral with the standard 1 and the head 23 being hinged, as shown at 26, to an arm 27 extending longitudinally from the top of the standards 2,

said arm 27 forming a support for the head 23 when it is swung outward and downward from the press. Said heads are tied together at the top by a tie rod 28, the ends of which are received in recesses 29 in upward extensions 31 from the heads 22, 23, and thumb nuts 32 are screwed upon the threaded ends of the rods to secure said heads in place.

The head 22 is formed on the outside with an extension 33, through threaded apertures in which and in the head 22 is screwed a threaded stem 34 carrying at its inner end a ball 36, which fits in a socket in a hub 37 located eccentrically upon a follower 38. Said stem 34 is turned by means of a pinion 39 having a key engaging a groove 41 in the threaded stem, and said pinion meshes with a gear wheel 42, rotatably mounted upon an extension 43 from the standard 1 and turned by a handle 44. It will be seen that, by turning the handle 44, the follower is advanced within the press but does not turn on account of its eccentric form.

Between two legs 46 of the standard 1 is located a spool 47 of twine, carried by a pin 48 supported in bearings in the legs 46.

I provide followers of different sizes, numbered, as shown at 49, and the hooks or teeth 19 are also numbered correspondingly, as shown at 51, so that the operator knows that when a follower having a certain number, as, for instance, number 5, is placed in the press, it is then necessary to press down the movable press section until the slotted catches 13 engage the teeth numbered 5.

The device is used in the following manner: The head 23 being dropped to a horizontal position, and the tie rod 28 being removed, the hinged press section is raised and the boned ham or other joint of meat is dropped into the stationary press section. The hinged press section is then dropped into position, the hooks 19 engaging the slots 14 in the catches 13, and pressure is applied to the handles 21 to compress the joint as much as possible, the catches 13 being engaged by lower hooks 19. Then the heads are tied together by means of the tie rod 28. The gear wheel 42 is then rotated until the joint is compressed between the head 23 and the follower 38. The head 23 is now dropped again into a horizontal position, and the joint is pressed by means of the follower through the open end of the press.

As it protrudes through said open end, it is bound by means of the twine supplied from the spool 47.

In Fig. 4 is shown a modification of the invention in which the lower press section is of a form suitable to contain a ham from which the boné has not been removed. In this case the bars 16 are of different sizes to correspond with the changed form of the press section. The spool 47 is omitted, and a handle 50 is applied directly to the threaded stem 34.

In the form of the invention shown in Figs. 5 and 6, upon a suitable base 51 is supported a rectangular press 52, open at one end, and at the opposite end closed by a downwardly swinging door 53 having spring catches 54 engaging angle irons 55 on the sides of the press. The top of the press is pivoted to the top of one side of the press and is closed by a door 56 having spring catches 57 which engage angle irons 58 on the other side of the press. It may thus be considered as a movable press section. From the bottom of the press at its open end extends a plate 59 on which is erected a standard 61 supporting a bearing 62, and through

said bearing is screwed a stem 63 having a handle 64. The inner end of the stem is formed with a circular groove 66, which is engaged by the inner ends of two screws 67, screwed through a hub 68 extending from a rectangular follower 69 movable in the press.

The mode of use of this form of the invention will be readily understood from the description and illustration thereof.

I claim:—

In a meat press, the combination of a stationary lower semi-cylindrical press section, an upper semi-cylindrical press section, hinged thereto on one side and having handles, catches on one of said press sections successively engaging lugs on the other press section, a follower within the press formed by said sections, means for advancing the follower longitudinally therein, a door for closing the end of the press toward which the follower advances, means for supporting said door when opened in a horizontal position immediately below the open end of the press to receive thereon from the press the article that has been compressed.

ALFRED M. DEMUTH.
